UNITED STATES PATENT OFFICE.

RALPH J. DAVIES, OF HARTFORD, CONNECTICUT.

CARD-INDEX APPARATUS

Application filed September 17, 1921. Serial No. 501,261.

To all whom it may concern:

Be it known that I, RALPH J. DAVIES, a citizen of the United States, residing at Hartford, in the county of Hartford and 5 State of Connecticut, have invented certain new and useful Improvements in Card-Index Apparatus; and I do hereby declare the following to be a full, clear, and exact description of the invention, such as will 10 enable others skilled in the art to which it appertains to make and use the same.

This invention relates to card indexes.

Principal objects of the invention are to increase the possibilities of classification with rectangular index cards by exposing to view two adjacent edges of each card in a drawer or other holder, thereby exposing greater length of card edge for receiving signal or indicator tabs as compared with the usual practice of exposing one edge for this purpose; and to facilitate the removal of any desired card.

The invention consists in a card holder adapted to hold a series of index cards 25 obliquely on two adjacent edges leaving the other two adjacent edges fully exposed; in index cards having signal tabs on two adjacent edges, and in the combinations and features of construction more specifically set forth in the ensuing description, defined in the appended claims and illustrated in the 30 accompanying drawings.

In the drawings in which like reference characters indicate like parts throughout the several views:

Figure 1 is a perspective of a card drawer made in accordance with this invention;

Figure 2 is a front elevation of a cabinet containing a plurality of drawers or holders like that shown in Figure 1;

Figure 3 is a cross section through a drawer containing square index cards;

45 Figure 4 is a perspective of a holder filled with oblong index cards and square separator cards; the front of the holder having been removed;

Figure 5 is a section through a desk holder embodying the invention.

The embodiment of the invention specifically illustrated and described herein involves a holder having two parallel longitudinal card-supporting members having their ends united to front and rear cross members, respectively. This holder may be so formed as to rest upon a desk or other support, and sustain rectangular cards with

two adjacent edges respectively sustained by the two longitudinal card-supporting members,—each card occupying a position with its edges at oblique angles with respect to a horizontal plane,—and exposing to view its other two adjacent edges. I have, in Figures 1 to 4, shown the card holder in the form of a drawer having a body of V-shape, a square front panel with a handle on its front side and a similar square back, said drawer adapted to slide in a cabinet provided with guides so constructed as to hold and guide said drawers with the diagonals of the square front and back parallel with the sides and bottom of the cabinet, or the apex of the V-drawer directed toward the base, the fronts of the drawers making a lozenge pattern, or pattern of oblique rectangles. In Figure 5 is shown a cross section of a holder adapted to rest on a desk or table. Followers, (not shown), may be used if found desirable according to common practice in card indexes. In Figures 1 to 4 numeral 1 indicates a card-holding drawer having parallel longitudinal card supports 2, illustrated as bars or strips having plane faces arranged at 90° to each other so that the lower corner of a rectangular card having adjacent edges resting thereon will depend between said bars, a perpendicular falling midway between the bars intersecting the corner of the card. The front ends of the card-supporting bars 2 are secured to a rectangular front panel 3 which occupies a transverse plane perpendicular to the bars 2. The rear ends of said bars are similarly connected to a rectangular or other suitable form of back 4. In the form shown in these views side walls 5 are secured to adjacent edges 3^a and 4^a of the front 3 and back 4 and may be also secured to the card-supporting bars 2, thus forming a drawer of trough shape the sides of which form an angle of 90° . Bars 2 are disposed equidistant from the junction of sides 5. The sides 5 serve as guides for keeping the drawer true while sliding in the ways of cabinet C and also prevent a card from accidentally slipping through a drawer. To the front side of the front panel 3 a handle 7 may be secured.

drawn from the cabinet or rests upon a table or desk. By reason of the increased length of exposed edge compared with the length of edge exposed in the ordinary card index 5 many more index or signal tabs 10, 11, may be attached to a series of cards so that an increased number of subjects may be classified. The cards may be arranged in a double classification, the tabs 10 on one edge indicating 10 one classification and the tabs 11 on the other edge another. Books, for example, may be classified according to subject matter by tabs 10 on one edge and according to language by tabs 11; for example, along the 15 margin adjacent edge 9 characters 12 indicating history, philosophy, science, fiction and poetry may be printed, and a tab 10 affixed in position appropriate to the subject matter on the card, while characters 13 indicating 20 languages as French, English, German, Spanish, Italian, may be printed along the margin adjacent the edge 9^a and a tab affixed in position appropriate to the language in which the indexed book is written. 25 Thus, by glancing along the line of tabs on one side all books on history, for example, can be selected, and by glancing along the lines of tabs on the other edge all books in the French language. Similarly an indefinite 30 number of other double classifications may be provided for, as the occupation and sex of employees; the names and residences of customers; the subject matter of legal decisions and the courts, whether Federal or 35 State, by whom the decisions were rendered.

In Figure 4 the rectangular index cards 18 are oblong, some of a series being inclined 90° to the others. By such an arrangement plural classifications may be conveniently 40 had in one holder. For example, subject matter in an index of legal decisions may form the basis of the major classification, and the nature of the courts from which the decisions are derived, another. Cards bearing 45 State court decisions may be indicated to the right and those bearing Federal court decisions to the left. This arrangement, it will be obvious, lends itself to convenient classification on any two bases of classification. In this form square separating cards 50 19 may be used to advantage, a small square corner section of a separation card being exposed at the space 20 formed by the crossed index cards. Index cards 18 of dimensions 55 4" x 6" are a convenient size for use. With cards of this size a 6" square separator card would expose a two inch square at the corner space between the two sets of oppositely inclined index cards for the reception of 60 indicia 21 indicating subdivision of major classification, (illustrated as an alphabetical classification in Figure 4). Thus, the index cards may be separated by the separators 19 into groups of surnames in accordance with 65 the initial letter thereof, and may be fur-

ther separated into native born and foreign born by the position of the cards, those inclined to the right bearing information relative to native born population and those to the left relative to foreign born. The signal 70 tabs 22, 23 may be positioned on the cards so as to indicate other facts.

In the desk holder illustrated in Figure 5, 2^a indicates the parallel members for engaging the lower adjacent edges of a series of 75 index cards and 24 indicates a plane bottom for sustaining the holder on a desk with two adjacent edges of the cards exposed to view for indexing purposes.

By supporting the cards on narrow, parallel card-supporting members any card or group of cards may be pushed downward on one edge, and thus caused to sway or shift its position slightly about an axis perpendicular to the card, depressing the edge or edges 80 with respect to adjacent cards, so that separation of a group by the fingers may be easily effected, or any card or group of cards 85 may be readily grasped and removed. This characteristic facilitates handling and selecting as compared with the usual card index in which the cards rest in a rectangular box with exposed edges in one plane, and not susceptible of being displaced edgewise with 90 respect to each other. 95

The front panels of the drawers may be right squares, as indicated in dotted lines in Fig. 3, instead of oblique squares as shown in Figs. 1 and 2. Right square panels support the drawers in proper position, should 100 they be placed upon a desk, although requiring a larger cabinet.

Having described my invention in the form now best known to me, what I claim and desire to secure by Letters Patent of the 105 United States is:

1. In a card index apparatus, a card holder, in combination with substantially rectangular index cards and means for sustaining 110 said cards on edge transversely of the holder with two adjacent edges fully exposed and lying oblique to a horizontal plane.

2. In a card index apparatus, a card index holder, in combination with substantially rectangular index cards and means for sustaining 115 said index cards transversely of the holder so that they may be rocked edge-wise and moved along said means in a direction normal to their faces in contact with said means, the edges of said cards lying oblique to a horizontal plane.

3. In a card index apparatus, a card holder having parallel spaced card-sustaining members, in combination with substantially rectangular index cards suspended 125 edgewise on said members, transversely thereof, said members engaging adjacent edges of the cards near opposite corners in such manner as to hold said cards with their edges oblique to a horizontal plane. 130

4. In a card index apparatus, a card holder having parallel spaced card-sustaining members having surfaces disposed at right angles to each other, in combination with substantially rectangular index cards resting edgewise on said members transversely thereof, said members engaging adjacent edges of the cards near opposite corners thereof.
5. In a card index apparatus, a holder having means to engage and guide index cards, in combination with substantially rectangular oblong index cards and means for sustaining them on edge transversely of the holder with two adjacent edges exposed and lying oblique to a horizontal plane.
6. In a card index apparatus, a card index holder having means to engage and guide index cards, in combination with substantially rectangular oblong index cards sustained on
- edge transversely of the holder with two adjacent edges exposed, and a square separating card having one side equal in length to the long side of the index cards.
7. In a card index apparatus, a card holder comprising a drawer having V-shaped sides adapted to sustain index cards transversely between them and a rectangular front panel, in combination with a cabinet in which said drawer slides, said cabinet holding the drawer with the apex of its sides directed toward the base of the cabinet.
8. In a card index apparatus, a card holder comprising a drawer having V-shaped sides, and offset, parallel card-guiding members on said sides disposed equidistant from the junction of said sides.

In testimony whereof I have affixed my signature this 17 day of June, 1922.

RALPH J. DAVIES.
